UNITED STATES PATENT OFFICE.

EDWARD JAMES LAHAN, OF QUINCY, ILLINOIS.

SPRING-HUB.

1,111,473.

Specification of Letters Patent. Patented Sept. 22, 1914.

Application filed July 22, 1913. Serial No. 780,596.

To all whom it may concern:

Be it known that I, EDWARD JAMES LAHAN, a citizen of the United States, residing at Quincy, in the county of Adams and State of Illinois, have invented a new and useful Spring-Hub, of which the following is a specification.

The present invention appertains generally to vehicle wheels, and relates more particularly to a novel and improved resilient or spring hub for automobile and other vehicle wheels.

It is the primary object of the present invention to provide a hub of peculiar and unique construction, which shall be operable to permit the vehicle wheel to yield vertically, in order that the wheel may have vertical relief when traversing a rough surface.

Another object of the present invention is to provide a device of the nature indicated embodying a novel assemblage of parts, in order that the present device will have superior advantages over existing devices of this character, and in order to best adapt the present device for the purposes intended.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The present invention has been illustrated in its preferred embodiment, in the accompanying drawing, wherein:

Figure 1 is an outside face view of the improved hub. Fig. 2 is a similar view with the face or cover plate removed to expose the interior mechanism. Figs. 3 and 4 are sectional views taken on the lines 3-3 and 4-4 of Fig. 1 respectively.

In carrying out the present invention, reference being had in detail to the drawing, there is provided a circular disk or plate 1 of relatively large thickness, and having a square or rectangular opening 2, the upper and lower ends of the opening 2 being provided with steps or bearings 3 adjoining the corners of the opening. In connection with the plate or body 1, there are employed two circular disks or plates 4, which are of larger diameter than the member 1, and which rest against the opposite sides of the said mem-

ber, the inner plate 4 forming a back plate, and the outer plate 4 forming a cover or face plate closing the opening 2. Thus, the member or body 1 together with the plates 4 constitute a case for the purposes which will hereinafter appear. The parts 1 and 4-4 are detachably secured together in order that they may be readily assembled and separated, and to this end, screws 5 are preferably passed loosely through the face plate 4 and member 1, so as to threadedly engage the back plate 4 to clasp the said parts tightly together. The peripheries or margins of the plates 4 extend beyond the periphery of the member 1 and an annulus or ring 6 is mounted for rotation between the edges of the plates 4, over the member 1, suitable roller or anti-frictional bearings 8 being preferably disposed between the annulus or ring 6 and the member 1 to permit the annulus to rotate freely. To the annulus 6, the spokes 7 are secured in any desirable manner, the details of which are of no particular moment. It is evident that the roller bearings 8 will be held between the annulus 6 and the member 1 by the plates 4, the annulus also being held for rotation between the said plates, in order that when the face plate is removed, the annulus, as well as the roller bearings, may be readily slipped off of the member or body 1.

The axle of the wheel has been designated by the numeral 9, the same being provided with a spindle 10 extending through vertically elongated openings or slots 11 provided in the central portions of the plates 4 midway between and parallel with the sides of the opening 2. A nut 12 is threaded onto the end of the spindle 10 to engage the face plate 4 for retaining the hub in position on the spindle, it being evident that the slots or openings 11 permit the casing embodying the members 1 and 4-4 to reciprocate or vibrate vertically.

A bearing block 13 embraces the spindle 10 within the member 1, and its upper and lower ends are provided with the notches or seats 14, while the sides of the bearing block 13 are provided with the projections 15 having their ends snugly engaging the sides of the opening 2 for sliding movements. Coiled wire compression springs 16 are disposed between the projections 15 and the respective steps or bearings 3, and between the seats 14 of the bearing block 13 and the ends of the opening 2 intermediate the steps

3, the upper and lower sets of springs working in opposition to each other, and tending to normally hold the bearing block 13 centrally of the hub structure.

5 Rectangular plates 17 are mounted on the spindle 10 over the inner and outer faces of the bearing block 13, the plates 17 having central openings through which the spindle passes. The projections 15 are greater in 10 width than the bearing block 13, so as to provide shoulders 18 engaging the side edges of the plates 17 which are disposed vertically, in order to maintain the plates in their vertical positions. It will be observed that 15 the plates 17 close the openings or slots 11, in order to exclude dust and other extraneous matter, the ends of the plates 17 being also adapted to strike the ends of the opening 2 to limit the vertical movements of the 20 vehicle wheel proper with respect to the spindle or axle. The bearing block 13 is so mounted upon the spindle 10, as to be constrained against rotation, whereby the member 1 carrying the annulus 6, will be restrained for vertical reciprocatory movements 25 against the tension of the respective springs 16. It may thus be said, that the bearing block is elongated and is disposed between and parallel with the upper and lower ends of the opening 2, with the ends of the block slidably engaging the sides of the 30 said opening. The block is provided with a central spindle-receiving aperture coöperating with the slots 11 and the sides 35 of the central portion of the block are spaced from the plates 4, while the end portions of the block are provided with projections 15 slidably engaging the plates 4 and forming the shoulders 18. The vertical plates 17 40 are disposed snugly between the sides of the central portion of the elongated block and the disks 4 and have their edges engaging the shoulders 18, the plates 17 having spindle-receiving apertures alining with the 45 aperture of the bearing block.

From the foregoing, taken in connection with the drawing, it will be evident that the vehicle wheel, or rather the tire thereof, may have vertical relief, to provide a cushion-

ing effect, or to absorb the shocks to which 50 the wheel is subjected in use. Thus, when the wheel is given an upward thrust, the member 1 will be forced upwardly against the tension of the upper set of springs 16, and after the upward thrust has been removed, the upper set of springs will recoil to 55 return the vehicle wheel to normal position against the tension of the lower set of springs. The other advantages of the present device will be manifest from the foregoing, without the necessity of a lengthy description, it being noted that the objects aimed at have been carried out satisfactorily.

Having thus described the invention what I claim to be as new is:—

A vehicle wheel including a circular body having a rectangular opening, disks of larger diameter than the body attached to the sides thereof, a spoke annulus mounted for rotation upon the body between the 70 disks, the disks having vertical spindle-receiving slots parallel with the sides of the said opening and midway therebetween, an elongated bearing block disposed between and parallel with the upper and lower ends 75 of the said opening and having its ends slidably engaging the sides thereof, the block having a central spindle-receiving aperture coöperating with the slots, the sides of the central portion of the block being 80 spaced from the disks and the end portions of the block having projections slidably engaging the disks and forming shoulders, vertical plates disposed snugly between the 85 sides of the central portion of the block and the disks and having their edges engaging the said shoulders, the plates having spindle-receiving apertures alining with the aforesaid aperture, and springs disposed between the block and the ends of the said opening. 90

In testimony that I claim the foregoing as my own, I have hereto affixed my signature in the presence of two witnesses.

EDWARD JAMES LAHAN.
